(57) **CLAIM**

The ornamental design for a magnifier, as shown and described.

DESCRIPTION

FIG. 1 is a top rear perspective view of a magnifier in a closed configuration, showing my new design;

FIG. 2 is a bottom front perspective view thereof;

FIG. 3 is a top view thereof.

FIG. 4 is a bottom view thereof.

FIG. 5 is a right side view thereof.

FIG. 6 is a left side view thereof.

FIG. 7 is a rear view thereof.

FIG. 8 is a front view thereof.

FIG. 9 is a bottom front perspective view of a magnifier in an open configuration;

FIG. 10 is a top rear perspective view thereof;

FIG. 11 is a top view of the magnifier in open position.

FIG. 12 is a bottom view of the magnifier in open position.

FIG. 13 is a right side view of the magnifier in open position.

FIG. 14 is a left side view of the magnifier in open position.

FIG. 15 is a rear view of the magnifier in open position; and, FIG. 16 is a front view of the magnifier in open position. The broken lines in the drawings depict portions of the magnifier that form no part of the claimed design.
